UNITED STATES PATENT OFFICE.

CHARLES A. LINDSTRÖM, OF PITTSBURGH, PENNSYLVANIA, ASSIGNOR TO PRESSED STEEL CAR COMPANY, OF PITTSBURGH, PENNSYLVANIA, A CORPORATION OF NEW JERSEY.

DISCHARGE-DOOR-OPERATING MECHANISM.

1,271,334.

Specification of Letters Patent.

Patented July 2, 1918.

Application filed August 17, 1917. Serial No. 186,680.

To all whom it may concern:

Be it known that I, CHARLES A. LINDSTRÖM, a citizen of the United States, residing at No. 138 Stratford avenue, Pittsburgh, in the county of Allegheny and State of Pennsylvania, have invented certain new and useful Improvements in Discharge-Door-Operating Mechanism, of which the following is a specification.

10 An object of the invention is to provide fluid pressure actuated means for automatically operating the discharge doors of a railway dump car.

15 Another object of the invention is to provide fluid pressure actuated means for automatically unlocking, locking and operating the discharge door mechanism of a railway dump car.

20 Another object of the invention is to provide means whereby the discharge doors of a railway dump car may be operated either by hand or automatically by fluid pressure.

25 Another object of the invention is to provide a discharge door operating mechanism for railway dump cars having a plurality of operating motors so constructed and connected together that the motors will operate consecutively.

30 Another object of the invention is to provide a discharge door operating mechanism for railway dump cars having a plurality of operatively connected operating motors, one of said motors being so constructed as to operate in advance of, and time the action 35 of, the other of said motors.

Another object of the invention is to provide a cushioned shock absorbing device for the door operating mechanism.

40 A further object of the invention is to provide a railway car discharge door operating mechanism which may be operated quickly without any direct manual labor, thus permitting a car or a plurality of cars to be dumped from a trestle or other place difficult of access without danger to an operator.

45 A further object of the invention is to provide a discharge door operating mechanism for a railway dump car, which, when applied to a plurality of cars suitably connected together, will operate the discharge door on any car in the train regardless of its relative location.

50 A still further object of the invention is to provide a discharge door operating mechanism for railway dump cars, which, when applied to a plurality of cars suitably connected together, will operate the discharge doors of any one or all of the cars in a train automatically and substantially simultaneously.

55 With the above and other objects in view, the invention resides in the construction, arrangements and combinations of parts hereinafter described.

60 Referring now to the drawings in which like reference characters refer to like parts, Figure 1 is a plan view of a car embodying the invention, portions of the car being removed to more clearly show the door operating mechanism; Fig. 2 is a side elevational view of the car showing the discharge door operating mechanism in position when the doors are open; Fig. 3 is an enlarged plan view of a portion of the car; Fig. 4 is an enlarged side elevational view of the car, portions of the door operating mechanism being shown in section. Figs. 5 and 6 are enlarged cross sectional views 70 taken on the lines 5-5 and 6-6 respectively of Fig. 1; Fig. 7 is an enlarged section through one of the motors taken on the line 7-7 of Fig. 3, the piston and piston head being shown in the door opening position; Fig. 8 is an enlarged sectional view 75 of the same motor taken on the line 8-8 of Fig. 2, the piston and piston head being shown in position when the doors are closed, and Fig. 9 is an enlarged sectional view taken on the line 9-9 of Fig. 1. Fig. 10 is an enlarged side elevational view of a portion of a car showing a modified form 80 of the locking and unlocking mechanism; Fig. 11 is a sectional view of the same taken on the line 11-11 of Fig. 10, and Fig. 12 is an enlarged sectional view taken on the line 12-12 of Fig. 11. Fig. 13 is a sectional view 85 of a four-way valve for controlling the pressure supply to the door operating mechanism, the valve in this figure being shown closed. Fig. 14 is a sectional view of the same showing the valve open to open the doors and also showing its connections to a railway car embodying the invention, and Fig. 15 is a sectional view of the same showing the valve open to close the doors.

Referring now in detail to the drawings, 1 indicates the underframe and 2 the body of the car, both of which may be of any suitable construction, and as an example are 5 shown in the drawings as of a construction described in the pending application of John F. Streib and myself for dump car construction, filed June 9th, 1915, and serially numbered 33,927—1915 series. The 10 underframe has been fully described in the application just referred to and may here be described briefly, as comprising side sills 3, 3, draft sills 4, 4 and bolsters 5, 5, all of which are suitably connected together. The 15 body 2 of the car has also been fully described in the above referred to application and may be described briefly as comprising sloping end floors 6, 6 and combined side walls and sloping side floors 7, 7, all of which are suitably connected together. The 20 lower portions of these sloping end floors and combined side walls and sloping side floors define the discharge opening 8 in the bottom of the car, which opening is controlled by doors 9, 9 preferably hinged near the sides of the car.

Each of the discharge doors 9 is provided with a beam 10 of any suitable section or 30 sections extending along and under its free edge and projecting beyond each end of the door. The ends of the beams 10, are connected through the medium of universally jointed links 11 to yokes 12, pivotally mounted in crank frames 13, 13, which are preferably located between the draft sills 4, 4 and at each end of the doors, that is to say, there is a pair of links 11 at each end of the discharge doors, one end of each of said 35 links being connected to the end of its respective beam 10, the other end of each pair of links being brought together and pivotally mounted in the yoke 12. Each of the crank frames is preferably journaled between the draft sills 4, 4 in such a position, 40 that when the discharge doors 9, 9 are closed, the links 11 and yoke 12 are on the dead center of the crank frame 13 or slightly beyond the dead center toward the sloping end floor, so that the load on the doors tends to 45 force the crank frame in the closing direction and thus automatically lock the doors against opening from jars or shocks during transit.

For operating the crank frames 13, shafts 50 55 14 and 14^a are provided, which are connected with the crank frames through the medium of safety clutches or lost motion devices 15 which are of the same general type as those described in U. S. Patents Nos. 1,002,856 and 1,012,260, granted to me. These shafts 14 and 14^a extend outwardly from the clutches and at their outer ends are journaled in suitable bearing members 16 which are preferably secured to the side 60 sill 3. The safety clutches 15 are intro-

duced for the purpose of permitting the dropping of the lading quickly without danger to the operator when the mechanism is operated by hand power and without danger of damage to the mechanism as a whole.

It is necessary that the crank frames 13 operate simultaneously to prevent undue strain on either side of the doors due to one crank frame operating before the other, also that the two crank frames move away 70 75 from the end sloping floors when the doors are being opened and toward such floors when the doors are being closed, which enables the placing of the crank frames closer to the floors and also allows the use of straight connections to the beams 10. For 80 the purpose of operating the mechanism by hand power a shaft 17 is provided having a squared end portion, to which a wrench or other suitable tool for rotating the shaft, 85 may be applied. This shaft is journaled in members 18 secured to the side sill and intermediate these members is provided with a pinion 19 which operatively engages a gear wheel 20 secured to a shaft 21 which 90 is also journaled in these members 18. This gear wheel operatively engages a gear wheel 22 which is secured to the shaft 14. The shafts 14 and 14^a are operatively connected together by a member 23 which engages the 95 gear wheel 24 on the shaft 14^a and the gear wheel 20. It will here be noted that the operative engagement of the gear wheel 20, and the operative engagement of the pinion 19 with the gear wheel 24 through the medium of the gear wheel 20 and the member 23 form a force increasing mechanism when 100 the discharge doors are to be operated by hand power.

The member 23 comprises a piston rod 25 105 having a toothed rack 26 adapted to mesh with the gear wheel 20 and a similar rack 27 adapted to mesh with the gear wheel 24. Intermediate its ends the piston rod 25 is provided with a piston 28 which is adapted 110 to contact with the wall of, and to travel within, the cylinder 29. This cylinder 29 may be secured to any suitable member of the car, but in the drawings is shown secured to the side sill 3, and is provided with 115 ports 30 and 31. Mounted on the rack 26 or integral therewith is a toothed member 32 with which a pawl 33, pivotally mounted in the members 18, is adapted to engage, thus locking the mechanism against accidental operation when the car is in transit. This pawl 33 is provided with an arm 34 which is operatively connected with the piston rod 35. The piston rod 35 extends into a cylinder 36 suitably mounted on the car, and is 120 provided with a piston 37 which is adapted to travel within the cylinder, which is provided with ports 38, 39 and outlet 40 to the atmosphere.

Each of the cylinders 29 and 36 is pro- 130

vided with an opening 36^a through which the inner surface of the cylinder and the piston may be lubricated. When the motors are in operative condition these openings in the cylinders are closed by plugs 36^b which are preferably screwed into the opening or may be closed by any suitable means.

41 indicates a pressure supply pipe which extends preferably from end to end of the car and may be provided with cocks 42 and 42. Between these cocks 42 and 42 the supply pipe 41 is provided with a branch pipe 43, which is connected with the port 38 of the cylinder 36. The port 39 is located some distance from the port 38 and is connected by a pipe 44 with the port 30 in the cylinder 29. 45 indicates another pressure supply pipe which extends preferably from end to end of the car and may be provided with cocks 46 and 46. Between these cocks the supply pipe 45 is provided with a branch pipe 48 which is connected with the port 31 of the cylinder 29.

When it is desired to automatically open the discharge doors, one of the cocks 42, 42 is closed and a pipe or hose from the fluid pressure supply is attached to the other cock and the valve 52 is opened. Fluid pressure is then introduced which enters the cylinder 36 through the supply pipe 41 and branch pipe 43 and moves the piston 37 a sufficient distance to lift the pawl 33 out of engagement with the toothed member 32. Immediately after the pawl has been lifted out of engagement with the toothed member 32 the piston 37 passes the port 39, permitting the pressure to enter the cylinder 29 through the pipe 44 and move the piston 28 in the direction indicated by the arrow in Fig. 4 of the drawings, a sufficient distance to fully operate the door operating mechanism. When the piston 28 is being moved in this direction by the fluid pressure, the air in the cylinder on the other side of the piston is allowed to escape to the atmosphere through the pipes 48 and 45. Between the port 39 and the outlet 40, the cylinder 36 is provided with an offset portion 49 which forms a stop for the piston 37 when such piston has passed the port 39, thus preventing the piston from passing the outlet 40 and the escape of the pressure through such outlet.

The operation of the crank frames and of their connections to the racks 26 and 27 has been fully described in the above referred to application and needs no further description here. When the piston 28 and piston rod 25 and the crank frames have traveled the prescribed distances, and the lading has been fully discharged the pressure from the fluid tank is cut off and the fluid in the pipe 41 is allowed to escape, thus permitting the spring 50 within the cylinder 36 to force the piston 37 to its normal position of rest, and the pawl 33 to re-

engage with the toothed member 32, as shown in Figs. 2, 4 and 8, thus placing the mechanism in proper position for the closing of the doors.

When it is desired to close the doors, cock 46 at one end of the car is connected with the fluid pressure and the fluid enters through pipe 45 and forces the piston 28 in the opposite direction to that indicated by the arrow in Fig. 4 of the drawings. The air in the cylinder on the other side of the piston escapes through the pipe 44 and outlet 40 in the cylinder 36 into the atmosphere. These reversals of the movement of the piston and consequently of the other movable mechanisms lifts the doors to the closed position, locks the mechanism and the car is ready for another load.

It will be seen from the foregoing description of the mechanism that the doors of a train of cars may be operated automatically and substantially simultaneously. By connecting the cocks 42 and 42 of adjacent cars, closing one of the cocks 42 at one end of the train, and then admitting pressure through the other cock at the opposite end of the train, the operation of the mechanism as hereinbefore described in connection with a single car, will be repeated throughout the train of cars, and the doors of all of the cars will be opened simultaneously or nearly so. By connecting the cocks 46 and 46 of adjacent cars, closing one of the cocks 46 at one end of the train and then admitting pressure through the other cock 46 at the opposite end of the train, the operation of the mechanism will be repeated throughout the train of cars, and the doors of all the cars will be closed simultaneously or nearly so. In operating a train of coupled cars, as just described, embodying the invention, it may be desirable to discharge the lading from certain of the cars and to leave the remaining cars of the train loaded so that they can be moved and discharged at some other place. In order to do this the branch pipe 43 of each car is provided with a stop cock 52 located between the supply pipe 41 and the cylinder 36 by means of which the fluid pressure supply may be shut off from the discharge door operating mechanism of the particular car or cars that it is not desired to discharge. By this means it is possible to discharge the load from any one car or series of cars in a train and at the same time retain the load in the remaining cars of the train.

In Figs. 10 to 12 inclusive a modification of the locking and unlocking mechanism has been illustrated in which the cylinder 36^c thereof is placed vertically so that the piston 37^a and the piston rod 35^a will operate in a vertical direction instead of in a horizontal direction, as described in connection with the preferred form. In this modification the

1 cylinder 36^a is provided with ports 38^a and 39^a which are connected with the pipes 43 and 44 respectively, and is also provided with an outlet 40^a. As the operation of the 5 piston relative to the ports and outlet is substantially the same as that of the preferred form, the hereinbefore description of such operation need not be repeated here. The spring 50 is arranged within the cylinder 10 36^a between the top of the piston and the inner top surface of the cylinder, and is adapted to force the locking pawl 33^a, through the medium of the piston and piston rod, downwardly into engagement with 15 the toothed member 32, thus locking mechanism against accidental operation. When it is desired to manually operate the mechanism, the operator first throws the pawl 33 out of engagement with the toothed member 20 32 by means of the cranked member 51, and then rotates the shaft 17 by the use of a wrench or other suitable tool, by which means the gears are operated in a manner described in the co-pending application for 25 patent hereinbefore referred to.

In operating the discharge door mechanism to discharge the load considerable momentum is attained in the moving parts including the doors and door operating mechanism, due to the sudden opening of the 30 doors and to the weight of the doors themselves and to the weight of the lading supported thereby, which momentum if it were not taken care of or absorbed in some manner might cause considerable damage to the 35 various parts of the door operating mechanism. To protect the mechanism against damage when the doors are being opened a shock absorbing device 53 is provided which 40 is attached to any suitable part of the car, in the path of the member 23. This device comprises a part 54 which is secured to any suitable part of the car and is provided with a hollow portion 55 within which a part 56 45 is telescopically mounted, such part 56 being held in operative position relative to the part 54 by a bolt 57 or other suitable means. The end portion 58 of this bolt is held against movement in the part 56 while the 50 end portion 59 is loosely mounted in the part 54, thus permitting the part 56 to move freely within the part 54. Within the hollow portion 55 and between the parts 54 and 56 a spring 60 is provided which, when the 55 member 23 strikes the part 56, will absorb the shock incident thereto. The end portion 59 of the bolt 57 is provided with a nut 61 which contacts with the part 54 and prevents excessive outward movement of the part 56. 60 Within the hollow portion 55 the part 54 is provided with a shoulder 62 against which the part 56 is adapted to abut and prevent excessive inward movement of the part 56. It is to be understood that the invention is 65 not necessarily limited to the specific con-

struction of the shock absorbing device as described herein, for it will be seen that any other suitable device may be used.

To more conveniently distribute the fluid pressure to the discharge door operating mechanism a four-way valve 63 may be provided, which may be connected with a pressure reservoir or other suitable pressure supply means located either on a locomotive or adjacent the railroad track. This valve comprises a shell 64 which is provided with openings 65, 66, 67 and 68, which are adapted to be opened or closed by a plug 69 mounted in the shell. The opening 65 is connected with the pressure supply means 70 by a pipe 70, and the openings 66 and 67 are connected with the pipes 41 and 45 by pipes 71 and 72 and hose 73 and 74 respectively while the opening 68 leads to the atmosphere. It will be noted that when the valve plug has been turned to the position as shown in Fig. 13 the fluid pressure from the supply means will be shut off from the pipes 71 and 72. When it is desired to open the discharge doors the operator turns the 80 valve plug to the position as shown in Fig. 14 and when in this position the plug directs the fluid pressure to the pipes 71 and 41 and cylinder 36, and at the same time directs the exhaust pressure from the cylinder 29 through the opening 68 to the atmosphere. 85

When it is desired to close the doors the operator turns the valve plug to the position as shown in Fig. 15 and when in this position the plug directs the fluid pressure through the pipes 72 and 45 and cylinder 29, the exhaust pressure from such cylinder being discharged to the atmosphere through the outlet 40 in the cylinder 36 as hereinbefore described. In Figs. 14 and 15 arrows 100 have been used to clearly show the directions which the fluid pressure is made to take by the valve plug.

I do not wish to be limited to the exact construction of the car, the door operating mechanism or the piping system for operating the cylinders as shown and described, for it will be understood, that the invention may be applied to any other suitable type of car and door operating mechanism without departing from the spirit and scope of the invention, for, what I claim as new and desire to secure by Letters Patent is:

Claims—

1. In a railway dump car, discharge doors in the bottom of said car, mechanism at the ends of said doors adapted to operate them simultaneously, and a plurality of operatively connected motors for operating said mechanism, one of said motors being adapted to time the action of the other of said motors.
2. In a railway dump car, discharge doors in the bottom of said car and having their meeting edges at substantially the longitudi-

- nal center line of the car, mechanism connected to each end of each door for operating said doors simultaneously, and a plurality of motors for operating said mechanism, one of said motors being so constructed and connected to the other of said motors that it will operate in advance of said other motor.
3. In a railway dump car, the combination with a plurality of discharge doors in the bottom of said car, of mechanism for operating said doors, a motor for operating said mechanism, a pawl adapted to coöperate with said motor to lock said mechanism, a motor for operating said pawl, and means for operatively connecting said motors, the last mentioned motor comprising means for timing the action of the first mentioned motor.
4. In a railway dump car, discharge doors in the bottom of said car, mechanism connected with each end of each door, and fluid pressure means for automatically operating said mechanism, said means comprising a plurality of operatively connected motors.
5. In a railway dump car, hinged discharge doors in the bottom of said car having opening movements in opposite directions, and a plurality of operatively connected fluid pressure motors for automatically operating said doors.
6. In a railway dump car, hinged discharge doors in the bottom of said car having their meeting edges at substantially the longitudinal center line of said car and having opening movements toward the sides of the car, a plurality of operatively connected motors for operating said doors, and means embodied in one of said motors for timing the action of the other of said motors.
7. In a railway dump car, discharge doors, having their meeting edges at substantially the longitudinal center line of the car, a plurality of operatively connected motors for operating said doors, connections between the ends of said doors and motors, and means for operating one of said motors in advance of the other of said motors.
8. In a railway dump car, a discharge door in the bottom of said car, a fluid pressure motor, connections from said door to said motor, a pawl adapted to coöperate with said motor for locking said connections, and a motor for operating said pawl.
9. In a railway dump car, a discharge door in the bottom of said car, a fluid pressure motor operatively connected with said door, a pawl adapted to coöperate with said motor for locking said door and a motor for operating said pawl.
10. In a railway dump car, a discharge door in the bottom of said car, a plurality of motors operatively connected with said door, means for operatively connecting said motors, and means for operating one of said
- motors in advance of the other of said motors, and a pawl operated by one of said motors and adapted to coöperate with the other of said motors for holding said door in closed position.
11. In a railway dump car, a discharge door, a fluid pressure motor, rack and gear means operatively connecting said door and motor, a pawl for locking said means, and a fluid pressure motor for operating said pawl.
12. In a railway dump car, a discharge door, a fluid pressure motor, rack and gear means operatively connecting said door and motor, a pawl for locking said means, a motor for operating said pawl, and means whereby one of said motors is caused to operate in advance of the other of said motors.
13. In a railway dump car, a discharge door, a fluid pressure motor, gear means operatively connecting said door and motor, a locking pawl, a motor operatively connected with said pawl and means for permitting one of said motors to operate in advance of the other.
14. In a railway dump car, a discharge door, a crank operatively connected with said door, a motor mounted on said car, means operatively connecting said motor and a crank, a pawl for locking said door, a motor for operating said pawl, and means for operatively connecting said motors.
15. In a railway dump car, a discharge door, a crank operatively connected with said door, a motor, means operatively connecting said crank and motor, means for locking said door in closed position, a motor for automatically operating said locking means and means operatively connecting said motors.
16. In a railway dump car, a plurality of discharge doors in the bottom of said car, a motor connected with said doors for automatically opening and closing them, means engaging said motor for holding said doors in closed position, and a motor for operating said means.
17. In a railway dump car, a discharge door, a crank connected with said door, an operating motor, a shaft connecting said crank and motor, a locking pawl for holding said door in closed position, and a motor for automatically operating said pawl, said motors being operatively connected together.
18. In a railway dump car, a discharge door, a crank connected with said door, a shaft for operating said crank, a gear wheel on said shaft, an operating motor comprising a cylinder, a piston and piston rod, a rack on said piston rod adapted to mesh with said gear wheel, a ratchet member on said rack, a pawl for engaging said ratchet member, and a motor for operating said pawl.
19. In a railway dump car, a discharge door, a crank connected with said door, a

- 6
- shaft for operating said crank, a gear wheel on said shaft, an operating motor comprising a cylinder, a piston and piston rod, a rack on said piston rod adapted to mesh with 5 said gear wheel, a ratchet member on said rack, a pawl for engaging said ratchet member, and a motor for operating said pawl, said motors being operatively connected together.
- 10 20. In a railway dump car, a discharge door, a crank connected with said door, a shaft for operating said crank, a gear wheel on said shaft, an operating motor comprising a cylinder, a piston and piston rod, a 15 rack on said piston rod adapted to mesh with said gear wheel, a ratchet member on said rack, a pawl for engaging said ratchet member, and a motor for operating said pawl, one of said motors being adapted to 20 operate in advance of, and time the operation of, the other of said motors.
21. In a railway dump car, a discharge door operating mechanism comprising a longitudinally movable member and connections therefrom to the doors, a motor for operating said mechanism, a pawl for locking said mechanism, a motor for operating said pawl, both of said motors being operatively connected together, a plurality of 25 pressure supply pipes, a connection from one of said supply pipes to the first mentioned motor for admitting pressure to said motor to close the discharge doors, and a connection from the other supply pipe to the second mentioned motor for admitting pressure to both of said motors to open the discharge doors.
22. In a railway dump car, a discharge door in the bottom of said car, mechanism 40 for operating said door, a fluid pressure motor for operating said mechanism, a pawl adapted to engage said motor and lock said mechanism, a motor for operating said pawl, said motors being operatively connected together, the last mentioned motor comprising a cylinder having an inlet port, an outlet port and an intermediate port, said intermediate port being connected with the first mentioned motor, and a piston in said cylinder 45 adapted to be moved back and forth past said intermediate port to alternately connect said port with said inlet or outlet port.
23. In a railway dump car, a discharge 55 door operating mechanism, a fluid pressure motor for operating said mechanism, a pawl for locking said mechanism, a motor for operating said pawl, said motors being operatively connected together, the last mentioned motor comprising a cylinder having an inlet port, an outlet port and an intermediate port, said intermediate port being connected with the first mentioned motor, and a piston in said cylinder adapted to be 60 moved back and forth past said intermediate port to alternately connect said port with said inlet or outlet port, said piston being movable in one direction by fluid pressure to connect said inlet and intermediate ports when the doors are being opened and movable in the opposite directions by other means to connect said intermediate port and outlet port when the doors are being closed.
24. In a railway dump car, a discharge 65 door operating mechanism comprising a longitudinally movable rack member, connections therefrom to the doors, and a shock absorbing device secured to said car adapted to arrest excessive movement of said member when the doors are opened.
25. In a railway dump car, a discharge 75 door operating mechanism comprising a longitudinally movable rack member, and a device secured to said car arranged to arrest excessive movement of said member and to absorb the shocks in said mechanism when the doors are opened.
26. In a railway dump car, a discharge 80 door operating mechanism comprising a longitudinally movable toothed member, and a device secured to said car with which said member is adapted to engage, said device being arranged to absorb the shocks on said mechanism when the doors are being opened.
27. In a railway dump car, a discharge 85 door, a crank connected with said door, a shaft for operating said crank, a gear wheel on said shaft, an operating motor comprising a cylinder, a piston and piston rod, a rack on said piston rod adapted to mesh with 90 said gear wheel, a ratchet member on said rack, a pawl for engaging said ratchet member, a motor for operating said pawl, and a shock absorbing device arranged to arrest excessive movement of said rack.
28. In a railway dump car, a discharge 95 door, a crank connected with said door, a shaft for operating said crank, a gear wheel on said shaft, an operating motor comprising a cylinder, a piston and piston rod, a rack on said piston rod adapted to mesh with said gear wheel, a ratchet member on said rack, a pawl for engaging said ratchet member, a motor for operating said pawl, said motors being operatively connected together, and a shock absorbing device arranged to 100 arrest excessive movement of said rack.
29. In a railway dump car, a discharge 105 door, a crank connected with said door, a shaft for operating said crank, a gear wheel on said shaft, an operating motor comprising a cylinder, a piston and piston rod, a rack on said piston rod adapted to mesh with said gear wheel, a ratchet member on said rack, a pawl for engaging said ratchet member, a motor for operating said pawl, one of said motors being adapted to operate in advance of, and time the operation of, the other

of said motors, and a shock absorbing device arranged to arrest excessive movement of said rack.

30. In a railway dump car, discharge doors in the bottom of said car, mechanism for operating said doors, a fluid pressure motor, rack and gear means operatively connecting said motor and said mechanism, a pawl for locking said rack, and a fluid pressure motor for operating said pawl to release said rack.

31. In a railway dump car, a pair of discharge doors, cranks connected with said doors, said cranks being movable in opposite directions, a motor for operating said cranks, connections from said cranks to said motor, a pawl adapted to be moved into and out of engagement with said motor, and a motor for operating said pawl, said motor being operatively connected with the first mentioned motor.

32. In a railway dump car, a discharge door, cranks operatively connected with the ends of said door, an operating motor comprising a cylinder, a piston rod extending beyond the ends of said cylinder, connections from the end portions of said piston rod to said cranks, a pawl adapted to be moved into or out of engagement with said piston rod, and a motor for operating said pawl, said pawl being movable out of engagement with said piston rod by means of fluid pressure and into engagement therewith by means independent of the fluid pressure.

33. In a railway dump car, a discharge door, mechanism for operating said door, said mechanism comprising a piston rod, and a device secured to said car with which said piston rod is adapted to engage when said door is being opened, said device being adapted to arrest the movement of said piston rod and to absorb the shocks in said mechanism.

34. In a railway dump car, discharge doors, mechanism for operating said doors, said mechanism comprising a motor having a pressure cylinder and a piston rod, and a device secured to said car adapted to arrest excessive movement of said piston rod when said doors are being opened, said piston rod being adapted to engage said device.

35. In a railway dump car, discharge doors, fluid pressure means for operating said doors, said means comprising a motor having a cylinder, a piston rod extending through said cylinder and beyond the ends thereof, rack members forming part of said piston rod, and a shock absorbing device secured to said car with which one of said members is adapted to engage when the doors are being opened, to arrest excessive movement of said piston rod.

In testimony whereof I affix my signature in the presence of two witnesses.

CHARLES A. LINDSTRÖM.
